UNITED STATES PATENT OFFICE.

FREDERICK A. KOLSTER, OF PALO ALTO, CALIFORNIA, ASSIGNOR TO FEDERAL TELEGRAPH COMPANY, OF SAN FRANCISCO, CALIFORNIA, A CORPORATION OF CALIFORNIA.

RADIO RECEIVING SYSTEM.

Application filed March 9, 1927. Serial No. 173,812.

This invention relates generally to a system and method of receiving signal energy of carrier frequency. It has special application to receiving systems employing a plurality of electron relays for repeating and amplifying signal energy.

It is an object of this invention to devise a radio receiving system and method which will minimize static disturbances and which 10 will give a high degree of selectivity.

It is a further object of this invention to devise a radio receiving system and method which will incorporate the idea of energizing an electron relay from a source of alternating current having a frequency above 15 audibility, as disclosed in my co-pending application No. 63,861 filed October 21, 1925.

It is another object of this invention to devise a novel radio receiving system and 20 method which will incorporate a number of electron relays coupled together in cascade and which are operated in such a manner that a side band frequency selected from a preceding relay is modulated in a succeeding relay.

Further objects of this invention will appear from the following description in which I have set forth the preferred embodiment of my invention. It is to be understood that 30 the appended claims are to be accorded a range of equivalents consistent with the state of the prior art.

Referring to the drawing:

The single circuit diagram illustrates one 35 embodiment of this system and method.

The invention may be explained in general terms as comprising a plurality of electron relays connected together in cascade. Each of the relays is energized from a local source 40 of alternating current having a frequency above audibility and which differs from the frequency of the signals to be received. Filter devices are employed for coupling together the successive electron relays and these 45 filter devices are tuned so as to select a side band frequency from the preceding relay for impressing the same upon the input of a succeeding relay. In practice the side band frequency which is selected out is the differential 50 frequency, which in the last relay stage may be of audible frequency.

Thus referring to the drawing there is shown a plurality of electron relays 10, 11, 12, and 13, the relays 10, 11 and 12 being employed as amplifiers while the relay 13 is em-

ployed as a detector or integrating device. Each of the relays is preferably of the three element type comprising the usual grid or control element 14, anode or plate 16 and electron emission element, or filament 17. The 60 input circuit of the first relay 10 is coupled to a suitable source of signal energy of carrier frequency, such as a loop antenna 18 which may be tuned by means of a variable condenser 19. The successive relay stages are 65 coupled together by means of tuned circuits or filter devices 20, 21 and 22 which may consist of ordinary coupling transformers having their secondary windings tuned by means of variable condensers 23.

In order to operate each of the relays as a modulator, each relay is associated with a local oscillator which produces alternating current at a frequency differing from the carrier frequency of the signals being received. 70 In practice it is also desirable to energize the electron relays with the current from this oscillator in a manner which I have described in my co-pending application No. 63,861 referred to above. Thus there is shown a local 75 oscillator 26 preferably operating at a frequency above audibility and which is coupled to supply oscillatory energy to the output circuits of the respective relays as by means of a plurality of coupling transformers 27. 80 This oscillatory current also serves as a convenient means for energizing the filaments 17 which have also been shown as coupled to the secondary of transformers 27 as by means 85 of variable condensers 28. As the relay 13 is being operated as a detector, it is provided with the usual grid condenser 29 and grid leak 30. The output of detector relay 13 supplies a suitable translator which has been indicated in the form of telephone receivers 90 95 31.

In operating the system which has been described above, the antenna or the input of relay 10 is tuned to the carrier frequency of the signal to be received. As relay 10 is being energized by periodically varying current differing in frequency from the carrier frequency, the carrier frequency will be modulated and the usual side band frequencies will be produced. One of the side band frequencies, preferably the differential frequency, is selected out by proper adjustment of filter 20 and is imposed upon the input of relay 11. As relay 11 is also energized from the oscillator frequency, this first beat fre- 100 105 110

quency will be modulated a second time in relay 11 to produce another set of side band frequencies. Filter 21 is then tuned to separate out the differential frequency produced by 5 this second modulation and this second differential frequency is imposed upon relay 12. In relay 12 the second differential frequency is modulated by the local oscillator frequency to produce another differential frequency 10 which is separated out by filter 22 and imposed upon the detector 13. In this last relay the differential frequency separated out by filter 22 is modulated to produce a frequency which is translated by the receivers 15 31.

By properly selecting the frequency of the local oscillator 26 with the frequency of the incoming signals, the differential frequency received by translator 31 is made an audible tone for the reception of telegraphic signals. In other words when filters 20, 21 and 22 are all adjusted so as to separate out the differential frequencies produced in a preceding amplifier for impressing upon a succeeding amplifier, a definite relation will exist between the frequency of the incoming frequency, the frequency of the oscillator and the tone frequency of the energy received by the translator 31. This relationship may be expressed by the following simple equation:—

$$N_0 = \frac{n_1 - t}{N}$$

Where

55 n_0 = Frequency of oscillator (cycles per second)

n_1 = Frequency received.

t = Tone frequency.

N = Number of tuned circuits.

40 However—

$$n_2 = n_1 - n_0$$

$$n_3 = n_2 - n_0$$

$$n_4 = n_3 - n_0$$

$$t = n_4 - n_0$$

45 Where n_2 , n_3 and n_4 are the differential frequencies to be produced in the outputs of relays 10, 11 and 12 respectively.

Now assuming the following values for n_1 , 50 t and N :

$N_1 = 100,000$ cycles = received frequency.

$t = 1,000$ cycles = signal or tone frequency desired.

55 $N = 4$ or the number of tuned circuits. Then

$$n_0 = \frac{100,000 - 1,000}{4} = 24,750 \text{ cycles.}$$

$$n_2 = 100,000 - 24,750 = 75,250 \text{ cycles.}$$

$$n_3 = 75,250 - 24,750 = 50,500 \text{ cycles.}$$

$$n_4 = 50,500 - 24,750 = 25,750 \text{ cycles.}$$

$$t = 25,750 - 24,750 = 1,000 \text{ cycles.}$$

Thus in the particular system disclosed, if the antenna is tuned to 100,000 cycles or 3000 65 meters, filters 20, 21 and 22 tuned to 3990,

5940 and 11,650 meters respectively, and the oscillator tuned to 1000 meters, a tone frequency of 1000 cycles will be produced in the translator 31.

Due to the fact that each relay stage is 70 tuned to a frequency differing from the received frequency and no two stages are tuned the same, the system is highly selective. Furthermore disturbances due to static and strays are minimized as the detuned coupling 75 transformers are not susceptible to shock excitation.

It is obvious that the detector relay 13 may be energized from the usual source of direct current if it is not desired to modulate after 80 the last amplifier relay. In this case if the frequency separated out by transformer 22 is well above audibility, the system may be used for the reception of telephonic signals.

I claim:

1. A method of repeating signal energy of carrier frequency characterized by the use of a plurality of electron relay amplifiers connected together in cascade, each relay having an anode connected to its output circuit, said method comprising maintaining operative anode potentials for the respective relays with periodically varying current, the frequency of said current being above audibility and serving to modulate repeated frequencies. 85

2. The method of repeating signal energy characterized by the use of a plurality of electron relay amplifiers connected together in cascade, each relay having an anode included in its output circuit, said method comprising maintaining operative anode potentials for the respective relays with periodically varying current whereby the energy repeated by each amplifier is modulated by a given frequency, and selecting a resulting frequency from each preceding amplifier and impressing the same upon a succeeding amplifier. 100

3. The method of repeating signal energy characterized by the use of a plurality of electron relay amplifiers connected together in cascade, each relay having an anode associated with its input circuit, an electron relay detector supplied from the last amplifier stage and a translator supplied by the detector, said method comprising maintaining operative anode potentials upon the respective amplifier relays from a source of periodically varying current having a frequency above audibility whereby the signal energy is modulated in each amplifier, selecting out the differential frequency from each preceding amplifier and impressing the same upon a succeeding amplifier, selecting out the differential frequency from the last amplifier and impressing the same upon the detector, and modulating the energy repeated in the detector to produce a signal of audible frequency in the translator. 110

4. In a signalling system, a plurality of 115 120 125 130

electron relay amplifiers connected together in cascade, each of said relays having an anode associated with its output circuit, filter means intercoupling said amplifiers, means 5 for coupling the first amplifier of the series to a source of signal energy of carrier frequency, local oscillator means for generating current having a frequency above audibility but differing from the carrier frequency, and 10 means for maintaining operative anode potentials on said relays with current supplied from said oscillator means whereby the energy repeated by each amplifier is modulated by the frequency of the oscillator, said filter 15 means being tuned to transfer only one resulting frequency from a preceding amplifier to a succeeding amplifier.

5. In a signalling system, a plurality of electron relays connected together in cascade and forming a multistage amplifier and a detector, said relays each having an anode associated with its output circuit, means for coupling the first relay of the series to a source of signal energy of carrier frequency, 20 local oscillator means for generating supersonic frequency current differing from said carrier frequency, means for maintaining operative anode potentials on said relays with currents from said oscillator means whereby the energy repeated by each relay is modulated 25 by the oscillator frequency, and filter means for coupling together each relay, each filter being tuned to transfer only resulting frequency to a successive relay.

6. In a signalling system, a plurality of 35 electron relays connected together in cascade, each relay having a filamentary electron emission element, said relays forming a multistage amplifier and detector, means for coupling the first relay of the series to 40 a source of signal energy of carrier frequency, a local oscillator for generating current having a frequency above audibility but differing from said carrier frequency, means for energizing the respective outputs 45 and electron emission elements of each relay with current from said oscillator whereby the energy repeated by each relay is modulated by the oscillator frequency, and filter means for coupling together each relay, each filter 50 being tuned to transfer only the differential beat frequency to a successive relay.

7. In a signaling system, a plurality of electron relays connected together in cascade, means for effecting a frequency change 55 for currents repeated in each relay, and filter means imposed between each relay and associated with the last relay of the series, the filter means associated with the output and input circuits of any one relay being tuned 60 to pass different frequencies whereby the frequency separated by the output is different from the frequency imposed upon the input circuit of the same.

In testimony whereof, I have hereunto set 65 my hand.

FREDERICK A. KOLSTER.
